UNITED STATES PATENT OFFICE.

EDWIN J. AKINS, OF MOUNDSVILLE, WEST VIRGINIA.

ROAD-BUILDING MACHINE.

1,161,016.

Specification of Letters Patent. Patented Nov. 23, 1915.

Application filed July 1, 1912. Serial No. 706,941.

To all whom it may concern:

Be it known that I, EDWIN J. AKINS, a citizen of the United States of America, and resident of Moundsville, county of Marshall, 5 and State of West Virginia, have invented certain new and useful Improvements in Road-Building Machines, of which the following is a specification.

This invention relates broadly to road building machines, and it has for its primary object to provide a mechanically propelled vehicle adapted for carrying and actuating, or propelling, rotary digging and grading devices.

15 A further object is to provide a road building machine of powerful construction adapted for operating scarifiers, earth conveyers, and the like, and for constantly advancing such devices.

20 A still further object is to provide a machine of the character mentioned wherein the vehicle and earth working tool carried thereby are driven independently, adapting it for varying the speed of the tool without 25 varying the speed at which the vehicle is advanced, and vice versa. And a still further object is to provide simple and conveniently operated means whereby the elevation of the earth working tool may be adjusted and 30 whereby said tool is rigidly held in adjusted position.

Another object within the contemplation 35 of the invention is to provide driving mechanism for the earth working tool, embodying a pair of drive-chains, with automatic means for equalizing the driving strain on said chains.

With these and other objects in view, the invention resides in the features of construction, arrangement of parts and combinations 40 of elements which will hereinafter be described, reference being had to the accompanying drawings, forming a part of this specification, in which—

45 Figure 1 is a side elevation of the invention; Fig. 2 is a view of the same with the engine removed, the same being partly in top plan and partly in a horizontal section; Fig. 3 is a front elevation of the invention; Fig. 4 is a cross section on the line 4—4, Fig. 1; Fig. 5 is an enlarged section through the gears of the countershaft; Fig. 6 is a section on the line 6—6, Fig. 2; Fig. 7 is a section on the line 7—7, Fig. 6; and Fig. 8 is an 50 enlarged section of the fly wheel and friction clutch.

55 Referring to said drawings, in which like designating characters distinguish like parts throughout the several views—1 indicates the side members of a vehicle frame which is supported on axles 2 and 3 in any suitable manner, the axle 2 being mounted upon wheels 4 and the axle 3 being mounted upon wheels 5. Said frame is adapted for supporting thereon an engine, as 6, which may be of any appropriate type. A variable speed transmission is interposed between the engine drive-shaft and the traction wheels, or drivers, 5 whereby the latter may be actuated to rotate on the axle 3, the transmission shown and hereinafter described being but one of various types which might be employed, but being preferred for the reason that it is admirably adapted for the use to which it is subjected in the present machine and is simple in its construction. Said transmission comprises a horizontally disposed crank-shaft or drive-shaft 7 journaled in suitable bearings on said frame and carrying a fly wheel 8, the crank 9 of said shaft being adapted for connection with the engine pitman (not shown). A friction clutch, preferably of the type illustrated in Fig. 8, is carried by the drive-shaft whereby the traction gearing may be connected and disconnected, said clutch being adapted to contact with the fly wheel, and comprising a normally stationary bushing 10 within which the drive-shaft and the inner end of the hub 11 of said fly wheel are rotatable. Fixed upon said bushing 10, so as to be rotated when motion is imparted to the latter is a pinion 12 in mesh with a gear wheel 13 carried by a countershaft 14 journaled on the frame; and slidable longitudinally on said bushing adjacent to said pinion is a sleeve 15 to which is pivotally connected the inner ends of toggles 16 having their opposite ends pivotally connected to radially movable sections or shoes 17 adapted to be forced into frictional engagement with the inner periphery of the fly wheel. A yoke 18 forming one of the arms of a suitably mounted bell-crank lever 19 is suitably connected to the sleeve 15 whereby, when a lever 20, under the control of the operator and connected to the opposite arm of said bell-crank, is manipulated, said sleeve is moved forward and back. As is obvious, when the lever 20 is thrust back, the sleeve 15 is thrust outward, forcing the shoes 17 into frictional engagement with the fly wheel, and rotation is thus

imparted to said sleeve and to the pinion 12 fixed thereon for communicating motion to the countershaft 14.

Located on the countershaft 14 is a plurality of gears, as 21, 22 and 23 of varying sizes, of which gears 21 and 23 are keyed on the shaft, as shown in Fig. 5, while gear 22 is loose thereon so as to be normally idle. Said gear 22 may, however, be rendered operative in any suitable well known manner, as by directing one or more pins 24 through registering holes provided in said gears 21, 22 and 23, as shown. Said gears 21 and 23 are adapted to be operatively engaged one at a time and respectively by gears 25 and 26 carried by a parallel shaft 27, while the gear 22 is continuously in mesh with a gear 28 interposed between and fixed to said gears 25 and 26. As is obvious, the gears 25, 26 and 28 may be arranged to shift on the shaft 27, or the said shaft may itself be arranged to be shifted, as shown in Fig. 2, for carrying any desired gear into operative relation to its companion gear on the countershaft 14 for changing speeds. As shown, the shaft 27 is longitudinally movable, a swivel-like connection being had between an operating screw 29 and said shaft, said screw having a crank or hand wheel 30 fixed thereto and operating through a stationary yoke 31 attached at a suitable point, as to the adjacent side member 1 of the frame.

In operative, or meshing, engagement with the gear wheel 28 throughout all shifting positions is the gear 32 of a spur-gear differential of the type illustrated in Figs. 6 and 7. The gear 32 and differential casting 33 are fixedly connected to a hollow shaft 34, one end of which has a pinion 35 fixed thereon in mesh with a spur gear 36 carried by and concentric with one of the drivers 5, while an internal gear 37 of said differential is fixed upon a shaft 38 having one end floating within said hollow shaft 34 and carrying a pinion 39 upon its opposite, or outer, end, which pinion meshes with a spur gear 40 carried by and concentric with the opposite driver 5. As is obvious, the provision of the differential permits the drivers to travel independently of each other for accommodating themselves to differences in the length of their paths of travel, as when the vehicle is rounding a curve.

55 The spur-gears 36 and 40, above mentioned, are supported upon angular braces 40' attached to the rims of the drivers, the purpose of such mounting being to relieve the wheel spokes of such strain as would result from mounting such gear directly upon the spokes, as is the usual practice.

60 The axle 3 is of that type known as floating, comprising two separated hollow shafts 41 and 42, which are separated by, and have 65 their adjacent ends rigidly connected to, a

differential housing 43. Operating within said housing and fixed upon a shaft 44 which is rotatably mounted within the hollow shaft 41 is the gear 45 of a spur-gear differential similar to the differential hereinbefore described as located intermediate the change-speed gears and the drivers. The internal gear (not shown) of said differential is fixed upon the adjacent end of a shaft 46 similar to shaft 44, which is rotatably mounted within the hollow shaft 42. The drivers 5 are rotatable upon the hollow shafts 41 and 42, which are stationary; hence, it will be apparent that the independently operating shafts 44 and 46 working within said hollow shafts are not subjected to any of the vehicle-driving or supporting strains.

70 The gear 45 of the differential of axle 3 is driven by a sprocket chain 47 which connects it with a sprocket wheel 48 on the drive-shaft 7, said chain operating through suitable openings, as 49, provided in the differential housing 43.

75 The rotatable shafts 44 and 46 have their outer ends projected outward from the corresponding ends of the hollow shafts 41 and 42, respectively, and carry thereon fixed sprocket wheels 50 which are connected by sprocket chains 51 to sprocket wheels 52 carried by the opposite ends of a shaft 53 which is journaled in the front ends of forwardly directed supporting bars 54 whose rear ends are loosely mounted on the outer ends of the hollow shafts 41 and 42. 80 The shaft 53 may be that of a rotary earth scarifier, excavator, conveyer, or similar device, a spiral earth shifting device or conveyer 55 being depicted in the drawings. Said supporting bars 54 serve as supports 85 for the earth-working tool and also to rigidly brace said tool at a fixed distance in front of the axle 3. For permitting a slight inclination from the horizontal of the earth working tool without straining or distorting the supporting bars 54, the latter are made in two sections, one section having swivel-like movement with respect to the other permitted by any suitable form of connection, as by a worm-screw 56 carried by one section operating within a threaded socket 57 formed in the adjacent section. Suitable braces, as the curved braces 58, are interposed between the front ends of the 90 rear sections of the bars 54 and a suitable fixed part, as the axle 3, whereby said bars are supported against lateral strains, said braces being loosely connected to the axle for permitting vertical rocking movement of said bars for a purpose which will presently be explained.

95 Having their lower ends mounted upon the hollow shafts 41 and 42 adjacent to the position of the supporting bars 54 on the latter are upright stanchions 59 whose 100

upper ends have rigidly fixed thereto suitable braces, as the inclined braces 60. Said braces 60 have yokes 61 formed on their ends adjacent to said stanchions, and rotatably mounted within the embrace of each of said yokes is an interiorly threaded sleeve 62 having a hand-wheel 63 fixed thereto, or formed integral therewith whereby it may be rotated. Extending through said sleeve 62 is the upper threaded end of an inclined rod 64 which has its lower end suitably connected to the foremost section of the adjacent supporting bar 54. By manipulation of the hand wheels 63, said supporting bars are raised and lowered for adjusting the level of the earth working tool. Serving to assist in supporting said stanchions 59 are braces 65 which have their upper ends fixed to said stanchions near the upper ends thereof and have their opposite ends resting upon the hollow shafts 41 and 42 near the differential housing 43.

As is obvious, the differential provided on the axle 3 has for its purpose to equalize the load on the sprocket chains in cases where the chains are of unequal length or have unequal tension, and thus to cause said chains to exert equal power for driving the earth working tool. Without such differential, unless the sprocket chains were so accurately adjusted as to be precisely equal in length, all of the load would be placed upon the chain having the greater tension. Further, if said chains were accurately adjusted, the load would soon be imposed wholly upon one or the other thereof owing to an unequal wear which will inevitably occur. Again, in operation, it is frequently found necessary to incline the earth-working tool more or less, elevating one end above the level of the other; and, in such case, the differential 45 serves to equalize the load on the sprocket chains. As has been explained, the employment of the two floating shafts and the differential gear equalizes the load on the chains, thus preventing the whole work of driving the tool from being imposed on one side or the other of the machine.

The machine is designed primarily for extremely heavy work, as road making, and is adapted for operating rotary scarifiers, conveyers, and like rotary tools interchangeably, such tools being mounted in the supporting bars 54, as shown.

In operation, the vehicle is advanced at one of the lower speeds, the speed used being determined by the character of work being done and by the character of earth acted upon. When it is desired to idle the earth working tool, as when it is desired to move the machine across country, the engine is stopped and the pins 66 directed through sprocket wheel 48 on the drive-shaft are withdrawn, idling said wheel. Said pins are

directed through said wheel and fixed disks 67 located on opposite sides of the wheel, as shown.

As is apparent, the pins 24 are employed only when it is desired to drive the vehicle 70 at a relatively high speed, as in moving across country, the gear wheel 22 at other times remaining idle.

Having thus described my invention, what I claim as new, and desire to secure by Letters Patent, is—

1. A traction road building machine, comprising a vehicle frame, an engine mounted on said frame, a drive-shaft driven by said engine, a hollow axle, traction wheels rotatable on said axle, means interposed between the drive-shaft and said wheels for driving the latter, a pair of rotatable shafts floating within said hollow axle and having their outer ends projecting outward from said traction wheels, sprocket wheels carried by the projecting ends of said shafts, a rotatable earth-working tool having sprocket wheels thereon, drive chains connecting the sprockets of the floating shafts to the 90 sprockets of said tool, a differential drive gear connecting the inner ends of said floating shafts, and means interposed between said drive-shaft and said differential gear for driving the latter.

2. A road building machine comprising a vehicle frame, an engine mounted on said frame, axles for supporting said frame, traction wheels rotatable on one of said axles, means interposed between the engine and said wheels and independent of said axle for driving said wheels, floating shafts forming a part of the one axle, means for driving said shafts, said driving means including a differential drive gear connecting the inner ends of said shafts, a rotary earth working tool, and means interposed between said shafts and said tool for driving the latter.

3. A road building machine comprising a vehicle frame, an engine mounted on said frame, axles for supporting said frame, traction wheels rotatable on one of said axles, means interposed between the engine and said wheels and independent of said axle for driving said wheels, floating shafts disposed within the one axle and having their outer ends projecting outward from said traction wheels, a differential drive gear connecting the inner ends of said shafts, a 110 rotary earth working tool, and means interposed between the outer ends of said shafts and said tool for driving the latter.

4. A road building machine comprising a vehicle frame, an engine mounted on said frame, axles for supporting said frame, traction wheels rotatable on one of said axles, means interposed between the engine and said wheels and independent of said axle for driving said wheels, floating shafts 125

- forming a part of the one axle, a differential drive gear connecting the inner ends of said shafts, driving means for said gear wholly dissociated from the wheel driving means,
5 sprocket wheels carried by said shafts, a rotary earth working tool having sprockets thereon, and sprocket chains interposed between the sprockets of the shafts and those of said tool.
- 10 5. The combination of a hollow vehicle axle, traction wheels rotatable on said axle, means for actuating said wheels, floating shafts operating within and having their outer ends projecting outward from said
15 axle, a differential drive gear connecting the inner ends of said shafts, a rotary earth-working element, means supporting said element at a fixed distance from said axle, and means interposed between said shafts and said element whereby rotary motion imparted to the former is communicated to the latter.
- 20 6. The combination of a hollow vehicle axle, traction wheels rotatable on said axle, means for actuating said wheels, floating shafts operating within and having their outer ends projecting outward from said

axle, a differential drive gear connecting the inner ends of said shafts, said means being independent of the wheel-actuating means, 30 bars pivoted at one end upon said axle, a rotary digging element journaled in said bars and supported thereby at a fixed distance from said axle, and means interposed between said shafts and said element whereby rotation of the former communicates corresponding rotation to the latter.

7. In combination, the hollow axle of a traction vehicle, said axle having traction wheels rotatable thereon, means for driving 40 said wheels, shafts floating within said axle, a differential drive gear connecting the inner ends of said shafts, supporting members connected to said axle, earth-working mechanism carried by said supporting members, 45 and means whereby motion imparted to said shafts is communicated to said mechanism.

In testimony whereof I affix my signature in presence of two subscribing witnesses.

EDWIN J. AKINS.
